UNITED STATES PATENT OFFICE.

EVELYN J. RUPERT ATKINSON, OF MELBOURNE, VICTORIA, AUSTRALIA.

PHONOGRAPH.

1,399,917.

Specification of Letters Patent. Patented Dec. 13, 1921.

Application filed November 3, 1919. Serial No. 335,339.

To all whom it may concern:

Be it known that I, EVELYN J. RUPERT ATKINSON, a subject of Great Britain, and a resident of Melbourne, in the State of Victoria, Australia, have invented certain new and useful Improvements in Phonographs, of which the following is a specification.

The invention relates to phonographs, and particularly to phonographs adapted to 10 produce sound from disk records.

An object of the invention is to produce a longer record on a given sized disk than is at present obtained.

Another object of the invention is to 15 prove the tone of the reproduced sound by causing the undulations or waves corresponding to a given note to be of the same length at all parts of the record groove.

Another object of the invention is to 20 provide a disk record in which the undulations corresponding to a given note are of the same length at all parts of the record groove.

Disk phonograph records consist of a disk having a spiral or radially progressing groove 25 therein, in which the undulations representing the sound waves are formed. The undulations may be vertical and formed in the bottom of the groove or may be lateral and formed in the sides of the groove. Since the groove progresses radially, and occupies the larger portion 30 of the area of the disk, the outer portion of the spiral groove is much longer than the inner portion of the spiral groove. When the disk is rotated at constant angular velocity, as is the usual procedure, the lineal 35 velocity of the outer portion of the groove is much greater than the lineal velocity of the inner portion of the groove. For instance, in a ten-inch record, the diameter of the 40 outer circle of the spiral groove is about nine inches and its length about twenty-eight inches, whereas the diameter of the inner circle is about four inches and its length about twelve inches. Since the disk rotates 45 at constant angular velocity, both in recording and reproducing, it follows that at the beginning of the record the groove moves at the rate of 28 inches per revolution, under the stylus, and at the end of the record at the 50 rate of 12 inches per revolution, under the stylus, so that the lineal speed of the groove with respect to the stylus is constantly varied during the recording or reproduction of the record. This causes the undulations 55 or waves in the outer part of the groove to be much longer than necessary and conse-

quently a much longer groove than necessary is required to reproduce a given selection. When the undulations are longer than necessary, a hissing sound is produced, as the stylus moves over the record, thereby interfering with the tone of the reproduction. 60

In accordance with my invention, I rotate the disk, both in recording and reproduction, at a constantly varying angular velocity, so 65 that the speed of the groove under the stylus is constant, thereby producing undulations (for a given note) of the same length or spacing at all parts of the groove.

The invention possesses other advantageous features, some of which, with the foregoing, will be set forth at length in the following description, where I shall outline in full, that form of my invention which I have selected for illustration in the drawings accompanying and forming part of the present specification. In said drawings I have shown one specific embodiment of my invention, but it is to be understood that I do not limit myself to such form, since the invention, as expressed in the claims, may be embodied in a plurality of forms. In the drawings I have shown the invention as applied to a sound reproducing apparatus, but it is to be understood that it may be applied in the 85 same manner to a recording apparatus.

Referring to said drawings:

Figure 1 is a side elevation of a portion of a phonograph showing one form of my invention applied thereto. 90

Fig. 2 is an underneath view of the record table, showing the driving mechanism.

Fig. 3 is a plan or top view of the record table with a record thereon.

In accordance with my invention, I drive 95 the disk record 2 at such varying angular velocity that the lineal speed of the spiral record groove 3, passing in contact with the stylus, is constant for all portions of the groove,—that is, the relative lineal speed of 100 stylus and groove remains constant, both in recording and reproducing, so that the length or spacing of an undulation or wave for a given note is the same at all parts of the spiral record groove.

In the drawings, I have shown a reproducing machine comprising a rotating table or disk record support 4, upon which the record 2 rests. Engaging in the groove 3 of the record is a stylus 5, secured to the 110 sound box 6, which is supported on the angularly movable tone arm 7. The needle en-

gages in the groove and travels substantially radially across the face of the record as it follows the progression of the groove. The lower face 8 of the table 4 is smooth and arranged below said table and parallel, or substantially parallel, to the radius thereof, is a shaft 9 which is rotated at constant speed by any suitable phonograph motor. The shaft is suitably supported in bearings 5 secured to the base 12 arranged below the table. The shaft 9 is approximately parallel to the path of the stylus 5 across the record and is provided with suitable driving means, such as the grooved pulley 13, which is connected to the motor driven pulley 14, by the belt 15. Splined to the shaft, so that it is rotatable therewith, and readily movable longitudinally thereof, is a wheel or roller 16, having a friction surface, such as rubber, 10 which is in frictional contact with the smooth under surface of the record table. The under surface of the table may be covered with a sheet of rubber, when desired, to increase the frictional contact, but a smooth, 15 metallic surface may be employed to advantage. The table bears with slight pressure against the wheel 16, so that there is a minimum of slippage between the wheel and the disk.

20 Means are provided for moving the wheel 16 radially of the disk in time and coincident with the radial progression of the stylus acting in the groove, so that the radial displacement of the wheel and stylus are always 25 the same. Preferably, the wheel lies directly under or substantially directly under the stylus. Connected to or secured to the tone arm 7, so that it moves angularly simultaneously and equally therewith, is an arm 30 17, concentric with the center of rotation of the tone arm. The arm 17 is provided at its outer end with a forked end 18 which embraces the wheel 16, causing it to move longi-

tudinally on the shaft 9 coincidently with the radial movement of the stylus. As the 45 wheel rotates at constant speed and moves radially in contact with the table in time with the radial movement of the stylus, the lineal speed of the groove under the stylus is constant at all parts of the groove. This 50 produces a uniform action on the stylus at all parts of the groove, producing uniformity of tone and permits the recording of a longer selection on a given-sized disk record than was heretofore possible with disk records 55 rotating at constant angular velocity.

I claim:

1. In a phonograph for reproducing from disk records, a rotatable support for the record, a rotatable shaft arranged parallel to 60 the surface of said support and disposed radially with respect to said support, a wheel engaging said surface and splined to said shaft, means for rotating said shaft, and means controlled by a record on said 65 support for moving said wheel longitudinally of said shaft.

2. In a phonograph for reproducing from disk records, a rotatable support for the record, a rotatable shaft arranged parallel to 70 and below the surface of said support and disposed radially with respect to the axis of rotation of the support, a wheel slidably and nonrotatively mounted on said shaft, means for rotating the shaft, and a lever 75 secured to the tone arm of the phonograph to extend radially therefrom and having a forked end embracing the sliding wheel so as to shift the same along its shaft under the control of the swinging movement of the 80 tone arm.

In testimony whereof I have hereunto set my hand at Pasadena, California, this 24th day of October, 1919.

EVELYN J. RUPERT ATKINSON.
